STOP-MOTION FOR PILE-WEAVING
MACHINES

Benjamin Kahn, Gadsden, Ala.

Application December 30, 1949, Serial No. 135,877

8 Claims. (Cl. 139—336)

1

The present invention relates to stop-motion arrangements for looms adapted to weave terry or cut pile fabrics.

In my co-pending application Ser. No. 123,545 and which is now Patent Number 2,547,824, dated April 3, 1951, filed October 26, 1949, I have disclosed a loom type machine of the character set forth above in which a reciprocable carriage, carrying a set of hooks, is periodically displaced from an inoperative into a thread engaging position in which the hooks engage certain warp threads to draw them into loops, the latter being then firmly anchored in the fabric by one or more traverses of the shuttle occurring while the carriage is retracted in inoperative position. In the particular form of machine disclosed, the carriage is normally held in its inoperative position by a retaining mechanism controlled in suitable manner, e. g. from a dobby-operated harness lever, so as to become momentarily inoperative in timed relationship with the movements of the lay or batten so that, during certain reciprocations of the lay, the carriage is enabled to carry out a similar reciprocatory movement at the end of which it returns to its inoperative position.

In the prolonged operation of a machine of this character it may happen that, owing to wear and tear, failure of lubrication or other causes resulting in the accidental jamming of some part, the retaining mechanism fails to respond properly to the operation of the controller and does not disengage the carriage. In such a case one or more rows of loops will be omitted in the pattern to be weaved and, unless the irregularity is noticed immediately, a considerable amount of time and material may go to waste.

It is, therefore, a primary object of the present invention to provide, in a machine of the character described, means for arresting the machine whenever the sequence of operations referred to above is not properly carried out.

More generally, however, it is an object of this invention to provide, in a loom or related machine, means for stopping its motion (or giving any other desired indication) whenever a first movement, executed by a control mechanism, is not followed in due time by a second movement, executed by a follower mechanism, which is to occur before the movement of the control mechanism has been completed.

The invention will be described with reference to the accompanying drawing in which:

Fig. 1 is a view similar to Fig. 2 of my above-identified application, representing a side-elevation of a loom provided with a stop-motion

arrangement according to the present invention, parts of the loom frame having been removed to expose the principal elements of the machine;

Fig. 2 is a top plan view, on a larger scale, of some of the elements shown in Fig. 1;

Fig. 3 is a side view on the line 3—3 of Fig. 2;

Fig. 4 is a side elevation of one of the switching devices forming part of the stop-motion arrangement according to the invention;

Fig. 5 is a top plan view of the device shown in Fig. 4;

Fig. 6 is an end view of the device illustrated in Figs. 4 and 5, shown in normal or unoperated position;

Fig. 7 is a view similar to Fig. 6, showing the device in off-normal or operated position;

Fig. 8 is a side elevation of another switching device forming part of the stop-motion arrangement;

Fig. 9 is an elevation of the same device taken from the side opposite that of Fig. 8, showing the device in off-normal or operated position;

Fig. 10 is a view similar to Fig. 9, showing the device in normal or unoperated position;

Fig. 11 is an end view of the device taken on the line 11—11 of Fig. 10;

Fig. 12 is a top view of the device in the position shown in Fig. 9;

Fig. 13 is a circuit diagram illustrating the electrical connection between the devices of Figs. 4—7 and 8—13, respectively; and

Fig. 14 is a graph showing the operation of the two devices in timed relation to that of other parts of the machine.

Referring first to Figs. 1—3, there is shown a machine 20 comprising a frame 21 whereon are supported the various elements of conventional horizontal loom of the Northrop type, including the warp beam 22, the take-up roll 23, guide rollers 24, 25, 26, the lay 27 pivoted at 28, a set of dobbies (not shown) selectively controlling the movement of various harnesses such as shown at 31a, 31b, 31c by way of wires 33a, 33b, 33c, respectively, which pass over rollers 34a, 34b, 34c and a motor 35 (Fig. 13) which actuates all of these elements in a manner not further described because well known per se. Fillings 110 are formed by weft threads supplied from suitable spools (not shown), in the shed 90 which in turn is formed by two sets of warp threads 90a and 90b, these warp threads passing from the beam 22 over guide rollers 24, 25, around rails 89, through the heddles of harnesses 31a, 31b, respectively, through the reed of the lay 27 and,

50 after having been turned into a fabric 38, around

rollers 24, 25, 26, the lay 27 pivoted at 28, a set of dobbies (not shown) selectively controlling the movement of various harnesses such as shown at 31a, 31b, 31c by way of wires 33a, 33b, 33c, respectively, which pass over rollers 34a, 34b, 34c and a motor 35 (Fig. 13) which actuates all of these elements in a manner not further described because well known per se. Fillings 110 are formed by weft threads supplied from suitable spools (not shown), in the shed 90 which in turn is formed by two sets of warp threads 90a and 90b, these warp threads passing from the beam 22 over guide rollers 24, 25, around rails 89, through the heddles of harnesses 31a, 31b, respectively, through the reed of the lay 27 and,

55 after having been turned into a fabric 38, around

rollers 24, 25, 26, the lay 27 pivoted at 28, a set of dobbies (not shown) selectively controlling the movement of various harnesses such as shown at 31a, 31b, 31c by way of wires 33a, 33b, 33c, respectively, which pass over rollers 34a, 34b, 34c and a motor 35 (Fig. 13) which actuates all of these elements in a manner not further described because well known per se. Fillings 110 are formed by weft threads supplied from suitable spools (not shown), in the shed 90 which in turn is formed by two sets of warp threads 90a and 90b, these warp threads passing from the beam 22 over guide rollers 24, 25, around rails 89, through the heddles of harnesses 31a, 31b, respectively, through the reed of the lay 27 and,

deflection roller 111, guide roller 26 and deflection roller 112 to the take-up roll 23.

Secured to the frame 21 adjacent the ends of its breast beam are a pair of slide boxes or guides 41, 141 within which move the slides 43, 143, respectively. Fig. 1 only shows the assembly 41, 141 positioned to the left of the operator (who stands at the right-hand end of the machine as viewed in Fig. 1), the other slide box and slide, positioned to the right of the operator, being illustrated in Figs. 2 and 3. Each slide carries at its front end a bracket 45, 145, respectively, serving as an anchorage for a respective pair of springs such as 46, 146, 147, these springs having their other ends anchored to pins such as 48, 148, 149 projecting from the boxes 41, 141. The tendency of these springs is to displace the slides rearwardly from the position shown in the various figures.

Each slide is provided at the underside of its rear extremity with a set of sawteeth 50, 150 co-operating with a dog 51, 151, respectively, the dog being pivoted to the associated slide box as shown at 152 for the dog 151. A vertical rod 54, 154, slidably guided in a sleeve such as 53 which is secured to the frame 21, is aligned with the rear extremity of the respective dog and has its lower end pivoted to a lever such as 55, rotatably held in the frame 21 by a stud 56. A spring 57, anchored to the frame 21 at 32, tends to maintain the left-hand end of lever 55 (as viewed in Fig. 1) and, with it, the rod 54 in a raised position in which the top of the rod abuts the dog 51, thereby positively maintaining the latter engaged with a pair of teeth 50 after the slide 43, in a manner subsequently described, has been brought into the position illustrated against the action of its springs; it will be understood that an identical arrangement, not shown, holds the rod 154 in the raised position shown in full lines in Fig. 3, thereby also maintaining the dog 151 engaged with a pair of teeth 150.

The two rods 54, 154 are adapted to be periodically depressed, against the action of spring 57 and its companion spring (not shown) associated with rod 154, by means of cams such as 61 which are mounted on a shaft 60 and co-operate with lever 55 and its companion lever, not shown. Motion is imparted to the shaft 60 by means of a cylinder or pulley 64 fixed to the shaft and having the end of a wire 66 wrapped around it, this wire passing around a guide roller 67 as well as a guide roller 58 and being fixed to a special dobby-operated harness lever or similar timing means, not shown, so as to be tensioned at predetermined intervals. A torsion spring 59, wrapped around the shaft 60 and fixed thereto at one end, is anchored to the frame 21 at 63 and tends to restore the cams to the position illustrated in Fig. 1 after they have been displaced therefrom by the action of wire 66 to effect the descent of rods 54, 154.

Bridged across the rear ends of the two slides 43, 143 are a pair of parallel beams 68, 69 which together with these slides form a reciprocal carriage generally indicated at 75. The inner or rear one of these two beams, beam 69, carries a hook bar 70; each slide further carries at its rear end a lug 71, 171, respectively, these lugs forming an abutment for a pair of plates such as 72 mounted on the forward face of the lay adjacent the two ends thereof. The positions of these lugs on their slides are adjustable by

means of screws 73, 173 passing through slots such as 174.

At the rear of the machine the frame 21 is provided with an extension 81 supporting a feed roller 83, a co-operating presser roller 84, a guide plate 85 and a deflecting roller 86, as well as a pair of brackets such as 82 in which there are journaled two further rollers 76, 77. Guide plate 85 is provided apertures 87 through which pass respective threads 90c, representing the pile warp from which the loops are to be formed. The threads 90c, which may be somewhat heavier than the ground warp 90a, 90b and which are supplied by separate spools or the like, not shown, enter between the feed roller 83 and the presser roller 84, thence pass around rollers 76 and 77 which cause them to travel along a short horizontal run in which they traverse the eyes of individual riders 78, and after passing around roller 86 and guide rails 89 enter the heddles of harness 31c. These threads, therefore, form part of the shed 90 previously referred to.

The riders 78 form part of a stop-motion arrangement for the pile warp which does not form part of the present invention and has been described in detail in my above-identified application.

Mounted on the shaft 91 of feed roller 83 is a gear 92 which meshes with another gear 93 mounted on a stud shaft 94. A plate 95, loosely pivoted on the stud shaft 94, carries a pawl 96 which is pivoted to the plate at 97. Pawl 96 co-operates with a ratchet 98, fixed to the stud shaft 94 so as to be rigid with gear 93, and is held in contact with the teeth of the ratchet by means of a spring (not shown). The end of roller 83 opposite gear 92 is embraced by the jaws of a brake member 80 which is pivoted to the frame 21 at 88 and frictionally engages the roller 83 to prevent overrunning and maintain the threads 90c at a certain tension.

Pivotedly secured at 101 to the plate 95 is a bent rod 100 having its other extremity fixed by a nut 103 to an upstanding portion of bracket 45. Forward displacement of the slide 43, resulting in a movement of rod 100 toward the right as viewed in Fig. 1, will thus swing the plate 95 counterclockwise around the stud shaft 94, thereby imparting a similar movement to the ratchet 98 and the gear 93, this in turn resulting in a clockwise rotation of gear 92 and roller 83.

The hook bar 70 carries a set of hooks 105 each having a shank 106 through which pass the mounting bolts 107 securing the hooks to the bar; each hook also has a bill 108, lying in the plane of the shank 106, and a fin-shaped part 109 extending perpendicular to that plane, all as clearly seen in Figs. 2 and 3. It should be noted that this form of hooks is shown merely by way of illustration and that they may be replaced, for example, with any of the hooks disclosed in my co-pending application Ser. No. 129,573, filed November 26, 1949.

The operation of the mechanism so far described is as follows:

Let us assume that, after the formation of shed 90 and the insertion of a filling 110 in the usual manner, the lay 27 has just moved into its forward (vertical) position indicated in dot-dash lines in Fig. 1. This movement of the lay causes the plate 72 and its companion plate, not shown, to impinge upon the lugs 71, 171, respectively, an action which slightly displaces the carriage 75 toward the front and momentarily releases the dogs 51, 151 from the grip of teeth 50, 150. Owing

to the presence of rods 54, 154, however, these dogs will remain in the position shown in Figs. 1 and 3, whereupon the lay returns to its position shown in full lines in Fig. 1. This cycle, therefore, constitutes the ordinary weaving operation in which a weft thread is thrown across raised and lowered warp threads which include the group warp 90a, 90b as well as the pile warp 90c.

During a subsequent cycle of operation, in which the harness 31c will be in raised position, the pile warp threads 90c will have been positioned in the path of movement of respective hooks 105. Let us assume that in this particular cycle a row of loops are to be formed. A short time before the lay 27 again reaches its vertical position, the control mechanism including wire 66, shaft 60, cam 61 and lever 55 will have caused the rods 54, 154 to descend into the position indicated in dot-dash lines for the rod 154 (Fig. 3). When now, the lay again strikes the lugs 71, 171, the dogs 51, 151 will be released and, by their own weight, will drop into the position shown in dot-dash lines for the dog 151 (Fig. 3) in which they rest on top of their respective rods. Now, as the lay recedes, the carriage 75 will follow it on its rearward swing because of the action of springs 46, 146, 147. The hooks 105 are thereby advanced toward the raised pile warp threads 90c until they come into engagement therewith.

When the lay 27 moves forward again, it pushes before it the carriage 75 whose hooks 105 now draw the threads 90c into loops. In the meantime the wire 66 has been released and the torsion spring 59 has restored the cams on shaft 60 to the position of Fig. 1. When, therefore, the carriage 75 has arrived in its forward position, spring 57 and its companion spring cause the rods 54, 154 to force the dogs 51, 151 into engagement with the teeth of their respective slides, so that the carriage 75 will be retained in that position during the following cycle or cycles of operation during which the loops previously formed will be firmly anchored to the body of the fabric.

When the carriage 75 first followed the lay 27 on its rearward swing, the rod 100 was displaced in such a sense as to cause the pawl 96 to pass over a number of teeth of ratchet 98; this number being preferably adjustable by varying the distance of the pivot 101 from the shaft 94. On the restoring (forward) movement of the carriage, during which the loops are formed, the rod 100 is withdrawn and rotates the plate 95 in such a sense that the pawl 96 will displace the elements 98, 93, 92 and 83 by an angle determined by the number of ratchet teeth previously skipped, thereby imparting the desired slack to the threads 90c. The amount of this slack should be regulated in accordance with the length of the loops, the latter being adjustable by changing the position of the lugs 71, 171 on the slides 43, 143.

The problem which I have set out to solve by my present invention is how to stop the machine (or in some other manner attract the attention of the operator) if, if for some reason, the carriage 75 fails to leave its forward position after the rods 54, 154 have disengaged the dogs 51, 151. For this purpose I provide a pair of switching devices, generally indicated at 200 and 300, which are respectively controlled by the carriage 75 (forming part of the follower mechanism) and by the control mechanism previously referred to. In the particular embodiment illustrated, device 200 (Figs. 2, 3) co-operates with the slide 143 while device 300 responds to the operation of rod 54. Device 200 is secured to the slide box 141 by an

arm 201 while device 300 is mounted directly on the frame 21 adjacent the rod 54.

Referring to Figs. 2-7 for a detailed description of the switch 200, it will be noted that the latter comprises a vertical supporting plate 202 attached, by means of screws 203, to the arm 201. An inclined arm 204 extends upwards from the plate 202 and froms a rest for the horizontal leg of an angle member 205 which is urged by a spring 206, secured to the plate 202 by a screw 207, toward the arm 204, this member being pivoted to plate 202 at 208. The vertical leg of member 205 has insulatedly mounted thereon a movable contact blade 209 which cooperates with a similar, stationary blade 210, the latter being insulatedly secured to a vertical arm 211 extending from the plate 202. As clearly seen in Fig. 4, blade 209 is held on the member 205 by means of a bolt 212, insulated from the blade by a dielectric sleeve 213, and is clamped between a pair of insulating washers 214, 215. Similarly, the blade 210 is clamped between washers 216, 217 by means of a bolt 218.

Suitable terminal tags 219, 220 are provided on the extremities of blades 209, 210, respectively, to which are connected the ends of leads or wires 221, 222.

The pivot 208 for the member 205 is represented by a rod which is anchored in two short lugs 223, 224 rising from the plate 202. The extremity of rod 208 opposite angle member 205 carries a normally horizontal arm 225, extending parallel to the horizontal leg of member 205, and both of these horizontal elements support a cam bar 226 extending parallel to the rod 208. It will be noted from Fig. 7 that the blades 209, 210, which are normally in conductive contact with each other, can be separated by a raising of cam bar 226 which causes angle member 205 to rotate about the rod 208 against the action of its restoring spring 206.

In Figs. 2 and 3 it will be seen that a bolt 227, serving to fasten the bracket 145 to the slide 143, also passes through a block 228 from which there extends a pin 229 towards the cam bar 226. Normally, i. e. when the carriage 75 is in its retracted position, the pin 229 will be spaced from the cam bar 226 as best seen in Fig. 2, being positioned forwardly of the bar. When, however, the carriage 75 is displaced toward the rear, in the manner previously described, the pin 229 engages the curved forward extremity 230 of cam bar 226, thereby raising the latter as illustrated in Figs. 3 and 7. From Fig. 3, where the pin 229 has been shown in dot-dash lines in its extreme rearward position, it will be noted that the bar 226 is long enough to stay raised as long as the pin is off normal, so that the contacts 209, 210 will remain open until the carriage has returned to its inoperative position.

Turning now to Figs. 8-12 for a description of device 300, it will be seen that a body member 301, secured by screw 302 to the frame 21, carries a fixed horizontal contact arm 303 and a movable contact arm 304 pivoted to the member 301 at 305. Pivoted to the fixed arm 303 at 306 is a swingable lever 307 provided at its lower extremity with a transverse bar 308, the latter forming an abutment for the lay 27 (see Figs. 1 and 10).

Each of the arms 303, 304 carries a respective contact blade 309, 310 which are normally out of engagement with each other, corresponding to the position of arm 304 illustrated in Figs. 8, 10 and 11. This position of the movable arm 304 is brought about by the lay 27 which, engaging the

bar 308, causes the upper extremity of lever 307 to coact with the cam-shaped underside 311 of arms 304 in such a manner that the latter will be swung clockwise, as viewed in Figs. 9 and 10, if the contacts had previously been in the closed position shown in Figs. 1, 9 and 12. Arm 304 is provided with a boss 312 co-operating with a spring-pressed pin 313, lodged in a bore 314 of body 301, to index the arm 304 either in its open-circuit or in its closed-circuit position; the bore 314 accommodates the spring 315 which is held in position by a threaded plug 316. A spring 317, anchored to the member 301 at 318, passes around the pivot 306 and engages the lever 307 to urge the latter into its normal position, shown in full lines in the several views, after displacement thereof by the lay 27 into the position indicated in dot-dash lines in Fig. 10, which displacement serves to trip the arm 304 into its open-circuit position.

Each of the contact blades 309, 310 is provided with a respective tag 319, 320 to which the leads or wires 321, 322 are connected. The blades are fastened to these arms in insulated relationship, in similar manner to that described for the blade 209, by means of bolts 323 and 324, respectively, and washers 325, 326 and 327, 328, respectively.

The rear end of arm 304 is recessed to form a shoulder 329 against which abuts the forward face of a spur member 330, the latter being pivoted to the arm 304 at 331 and normally held in contact with the shoulder 329 by a spring 332 which embraces a stud 333 on the arm 304. The spur portion of this member extends into the path of a collar 334, secured to the rod 54, which is normally above the arm 304 as shown in Fig. 1 and in full lines in Fig. 10. When this collar descends with the rod 54 into the position shown in dot-dash lines in Fig. 10, it will displace the spur member 330 against the action of the relatively weak spring 332 without displacing the arm 304 from its normal position in which it is held by the coaction between pin 313 and boss 312. On the subsequent rise of the rod 54, however, the collar 334 engages the spur member 330 from below, causing it to bear upon the shoulder 329 and thereby effecting a rotation of the arm 304 into its alternative position in which its contact blade 310 touches the stationary blade 309, thus closing a circuit which is not opened until the lay 27 displaces the lever 307 in the manner previously described.

As illustrated in the circuit diagram of Fig. 13, the contacts 209, 210 and 309, 310 are connected in series with each other and with the winding of a relay 335. Motor 35 is energized from a main power supply 336 in a circuit which includes break contacts 337 of relay 335, the energizing circuit for the motor including an auxiliary source of current 338 as well as the leads 221, 222, 321 and 322. Thus it will be seen that simultaneous closure of both sets of contacts will cause the relay 335 to operate, breaking the energizing circuit of motor 35 and arresting the machine.

Turning to the timing diagram of Fig. 14, curve 27 denotes the reciprocations of the lay (upper peaks indicate forward position), curve 75 denotes in similar manner the displacement of the carriage by and in step with the lay, curve 54 denotes the rise and fall of rod 54, curve 300 indicates the periods of closure of contacts 309, 310 and curve 200 similarly indicates the period of closure of contacts 209, 210; finally curve 335 denotes the operation of the relay of Fig. 13. Several cycles of operation are indicated by the intervals A, B, C, D and E. Thus,

in the interval B, there occurs a normal operation of the loop forming mechanism, initiated by a descent of rod 54, followed by a movement of the carriage (the striking of the carriage by the lay during each cycle being represented by the low peaks 75') which causes the switch 200 to open before the switch 300 closes its contacts, and ending with the re-opening of switch contacts 309, 310 by the lay 27 just before the carriage 75 returns to home position, reclosing contacts 209, 210. Hence there occurs at no instant a simultaneous closure of the contacts of both switches.

In the interval E, however, it has been assumed that on account of some defect the carriage 75 remains in its position; contacts 209, 210 will now remain closed while the rise of rod 54 closes the contacts of switch 300, thus resulting in the energization of the relay 335. The circuit of motor 35 is now opened at contacts 337 and the machine comes to a stop.

It should be understood that the invention is by no means limited to precise form or mode of application described and illustrated; on the contrary, it is capable of numerous modifications and adaptations as well as use with other types of machinery without departing from the scope and spirit of the invention as defined in the objects and in the appended claims.

I claim:

1. In a loom, in combination, a reciprocable lay, a reciprocable carriage, retaining means normally holding said carriage in an inoperative position remote from said lay, control means periodically inactivating said retaining means in timed relationship with the movement of said lay, operating means effective upon inactivation of said retaining means to displace said carriage in the direction toward said lay to an operative position, return means including the lay effective upon displacement of said carriage to return the latter to said inoperative position, a first switching device actuated by said carriage to assume an off-normal position as long as said carriage is displaced from its said inoperative position, a second switching device actuated by said control means to assume an off-normal position subsequently to the beginning of the normal displacement of said carriage, restoring means operative prior to the normal return of said carriage into said inoperative position to restore said second switching device to its normal position, a motor controlling the movement of said lay, and circuit means for stopping said motor, said circuit means being rendered effective only in the normal position of said first switching device upon said second switching device simultaneously occupying its said off-normal position.

2. The combination according to claim 1 wherein said control means includes a control member moving in one direction to inactivate said retaining means and subsequently moving in the opposite direction to return said retaining means to the active position thereof prior to the return of said carriage to said inoperative position, said control member displacing said second switching device toward said off-normal position thereof upon moving in said opposite direction only.

3. The combination according to claim 2 wherein said control member comprises a rod provided with an abutment, said second switching device comprising a movable arm provided with an extension displaceable relative to said arm, spring means tending to maintain said ex-

tension in a predetermined position relative to said arm, said extension in said predetermined position projecting into the path of said abutment, and stop means limiting displacement of said extension relative to said arm in the direction induced by movement of said rod in the direction of the latter for returning said retaining means to its active position.

4. The combination according to claim 3 wherein said movable arm carries a first contact element, said second switching device further comprising a second, stationary contact element engaging said first contact element only in said off-normal position of said second switching device.

5. The combination according to claim 1 wherein said first switching device comprises a movable arm, said carriage being provided with cam means displacing said movable arm upon displacement of said carriage from its inoperative position.

6. The combination according to claim 5 wherein said movable arm carries a first contact element, said first switching device further comprising a second, stationary contact element engaging said first contact element only in the normal position of said first switching device.

7. The combination according to claim 1 wherein said restoring means is actuated by said lay.

8. In a loom, in combination, a reciprocable

lay, a reciprocable carriage movable at intervals between an inoperative and an operative position in timed relationship with the movement of said lay, a first normally closed switch actuated by said carriage to assume an open position so long as said carriage is displaced from said inoperative position, a second normally open switch, means operating in coordination with said lay to actuate said second switch to closed position subsequently to the normal beginning of the movement of said carriage toward operative position, restoring means operative prior to the normal return of said carriage to its inoperative position to restore said second switch to open condition, a motor controlling the movement of said lay, and circuit means for stopping said motor, said circuit means being rendered effective only when said first and second switches are simultaneously closed.

BENJAMIN KAHN.
